UNITED STATES PATENT OFFICE.

THEODORE WATSON, OF EAST MELBOURNE, VICTORIA, AUSTRALIA, ASSIGNOR TO WATSONIA ENGINEERING AND MANUFACTURING COMPANY PROPRIETARY LIMITED, OF MELBOURNE, AUSTRALIA, A CORPORATION OF VICTORIA.

RECORD-BRUSHING ATTACHMENT FOR GRAMOPHONES.

Application filed July 7, 1927, Serial No. 203,906, and in Australia July 19, 1926.

One object of this invention is to provide an attachment for gramophone sound boxes and to make it easy to fasten it to sound boxes of various dimensions and contours.

5 A further object is to make the cleaning member, hereinafter called the brush, easily adjustable with its working edge bearing in the most effective position on the record relatively to the needle, and so that it will 10 sweep the groove from beginning to end. Sound boxes are differently located in different machines relatively to record grooves, and tone arms swing in various ways relatively to the records. The tone arm pivots 15 also differ in positions. Adjustability of the brush is consequently essential to secure the best cleaning effect. Sound boxes having different contours cannot all be satisfactorily gripped by ordinarily known means, 20 and in order that almost every form of sound box known to me may be firmly gripped, I provide the features herein described.

I illustrate in the drawings herewith an 25 embodiment of my invention, but the construction may be modified while retaining features hereinafter claimed. The attachment is shown enlarged, and the scales vary.

Figure 1 is a plan of my attachment fitted 30 to a sound box, part of a record being also shown.

Figure 2 is a sectional elevation on line 2—2 of Figure 1.

Figure 3 shows, in perspective, the attachment frame without the brush.

Figure 4 shows, in perspective, a brush and its means for attachment to the frame.

Figure 5 shows, in perspective, part of a 40 frame having on its fixed jaw an auxiliary removable lug.

A sheet metal frame or body 1 carries jaws to grip the rim R of the sound box S, and has a wing 2 to support a brush B below the sound box.

45 A fixed jaw J¹ extending from the body, and an adjustable jaw J², extending from a limb 1^a of the body, grip the sound box rim between them, each extension being at a right angle with the body. The adjustable 50 jaw is shown concave to enable its edges which are shown serrated to grip, and this jaw is slidable on the limb 1^a, and is pressed into gripping position by a nut 1^b on the limb, which is screwthreaded. The adjust-

able jaw has a rigid channelled tail J³ extending at an angle from it, the body 1, fitting in the channel according to the tail adjustment, this tail preventing rotation of an adjustable jaw J², the body acting as a firm abutment when the attachment is fixed. 55 I fit on jaw J¹, opposite part of jaw J² a lug or auxiliary jaw J⁴ which grips part of the sound box when required instead of or in addition to jaw J¹ doing so, according to the particular contour to be gripped. 60 65

The rear of the member J⁴ has a slot or a channel having walls 3 to engage jaw J¹, enabling the said member to be slid along jaw J¹ into any location appropriate to the contour of the sound box in use. The gripping edge of said auxiliary jaw is shaped 70 with points 4 which bite or hold the sound box surface.

The attachment has a neck N supporting 75 wing 2 which has a curve seen in plan view, its location being clear above the record, see Figure 2. To enable the brush to work effectively on every part of the grooving while the record rotates in the direction D shown by an arrow, the use of a curved wing is 80 important.

This wing has a slot 5 carrying a fitting 85 which supports the brush B, and that fitting extends to and locates the brush on the concave side of the wing, that is the side facing the needle S¹.

The brush is removable at will, its stock fitting a socket B², for example. The socket connects with wing 2 by a lug T which is bendable, this lug being satisfactory when 90 of somewhat springy sheet brass.

To adjust the lug T and support it, its head 6 has a ridge 6^a which fits into and is slidable in slot 5, means being provided to fix this head temporarily in any adjusted 95 position. The means shown comprise a pin 7 having on its head a ridge 7^a. A hole 6^b in the ridge 6^a receives the pin 7 the ridge of the head of which fits the channel which constitutes the interior of the ridge 6^a. The 100 pin is screw threaded and carries a clamp nut 7^b.

To fit this attachment in place the brush does not need to be set accurately at first, though it is convenient to set it approximately correctly relatively to the record. The distance between the jaws J¹, J², or J⁴, J², is regulated to cause them to grip 105

the sound box. Then the brush should be brought into accurate working position by sliding the head 6 along groove 5 until the brush outer edge covers the first groove G 5 of the record when the needle is in that groove. The plug T will be bent suitably to secure the desired true bearing of the brush on the record surface.

I claim:—

- 10 1. A mounting for a phonograph record brush, comprising in combination, a clamping member adapted to be secured to the sound-box, a downwardly bent curved slotted wing fixed to the clamping member and
- 15 2. A mounting for a phonograph record brush, comprising in combination a body part of the clamping member, a fixed jaw forming arm on the said body part, a movable jaw adjustably mounted on the body part, the two jaws being adapted to be clamped from both sides to the rim of the sound box, means for fixing the adjustable jaw in the sound box clamping position, a downwardly bent curved slotted wing on the said body part, and a brush carrier fixed adjustably in the slot of the said curved wing.
- 20 3. A mounting for a phonograph record

brush, comprising in combination, a clamping member adapted to be secured to the sound box, a downwardly bent curved wing fixed to the said clamping member and having a slot extending over the length of its 35 curved lower part, a brush carrier, an upwardly bent arm on the brush carrier, having a slide forming upper end, adapted to slide within the said slot, and means for fixing the slide forming end of the said arm at a chosen position within the said slot.

4. A mounting for a phonograph record brush, comprising in combination, a body part of the clamping member, a fixed arm on the said body part, a lug adjustably secured to the said fixed arm, and having gripping edges adapted to hold or bite the one side of the sound box surface, a movable jaw adjustably mounted on the body part, and having a bent face with tooth like serrated edges, adapted to hold or bite the other side of the sound box surface, a nut screwable on the body part for fixing the movable jaw in the sound box clamping position, a downwardly bent curved wing on the said body part, and a brush carrier fixed 45 adjustably to the said curved wing.

In witness whereof I have hereunto set my hand.

THEODORE WATSON.
